FEELER DEVICE FOR LOOMS.

1,258,727.

Specification of Letters Patent. Patented Mar. 12, 1918.

Application filed June 27, 1916. Serial No. 106,251.

To all whom it may concern:

Be it known that we, GEORGE E. WHITEHEAD and JAMES F. MARSHALL, citizens of the United States, residing at Millbury, in the county of Worcester, State of Massachusetts, and Whitinsville, town of Northbridge, in said county and State, have invented a certain new and useful Improvement in Feeler Devices for Looms, of which the following is a specification, reference being had therein to the accompanying drawings.

The invention has relation to feeler-devices such as are employed in looms for detecting when the supply of weft or filling contained in a shuttle on the lay of a loom has become depleted to a predetermined extent.

The invention consists, essentially, in a feeler-tip of novel and improved form and construction for feeler-motions of the general class represented by that of U. S. Letters Patent No. 1,127,086, granted Feb. 2, 1916. Thereby an improved action and certain advantages in use are attained.

The drawings show the invention.

Figure 1 of the drawings is a plan view of portions of a loom with a feeler-tip embodying the invention applied thereto.

Fig. 2 is a plan view of the feeler-tip, shown separately on an enlarged scale.

Fig. 3 is an edge or side view thereof.

Having reference to the drawings,—

The main features of the feeler-motion shown in Fig. 1, as in the case of that shown and described in Letters Patent No. 1,127,086, comprise a laterally displaceable feeler-member 1 furnished with a feeler-tip 2 of a slipping type, an actuator 3 that is combined operatively with the said feeler-member, a carrier 4 for the feeler-member and actuator, arranged to swing around a pivotal mounting 4^a upon a feeler-stand 5, and a controller 6 pivoted at 7 upon the said feeler-stand and adapted to be actuated by the actuator 3, and also arranged to control the latch, catch, or dog 8 of the devices for calling a change in the operation of a loom.

The general construction shown in Fig. 1, taken as a whole, is of a later design than that shown in Letters Patent No. 1,127,086, and the specific construction of the parts that have been named varies from that

shown and explained in such Letters Patent. In addition, the said general construction includes the features of the present invention, as well as various specific features of invention that have been made the subject of separate application for Letters Patent. A brief description of the said general construction and the mode of operation thereof will be given first, by way of making clear the particular nature of the invention itself, and its special aims.

As in Letters Patent No. 1,127,086, the feeler-member 1 in Figs. 1 and 2 of the accompanying drawings is the more immediate support and carrier for the actuator 3, and lateral displaceability of the feeler-member is provided for by arranging it to swing in a horizontal plane around a pivot 9 on the feeler-carrier 4. Also, by means of a contracting spiral spring 10 the feeler-member is held normally against a stop 11 upon the feeler-carrier 4 in a position such that the actuator will miss the engaging end-piece 6^a of controller 6 if the feeler-carrier 4 is swung forward around its pivot 4^a with the feeler-member in contact with such stop. As in such Letters Patent, also, the feeler-carrier normally is held in a rearward position by the action of a suitable spring (herein designated 24) and the feeler-tip 2 projects rearwardly from the feeler member in position to enter slots 12 and 13 in the shuttle-box front-plate 14 and the front wall of shuttle 15, respectively, as the lay 16 beats up with the shuttle in the shuttle-box at the feeler-side of the loom, so that the feeler-tip shall receive against its acting extremity the blow or pressure of the shuttle-contents.

The mode of operation, in general, of the feeler-motion of Fig. 1 resembles that in the case of the feeler-motion shown in Letters Patent No. 1,127,086. Such mode of operation may be stated briefly as follows: As in the said Letters Patent, so long as the weft-carrier *a* within the shuttle continues to hold a sufficient thickness of weft or filling *b* to prevent the extremity of the feeler-tip 2 from slipping lengthwise of the weft-carrier under the effect of the forward blow or pressure against such extremity, the actuator goes forward at one side of the engaging piece 6^a of the controller 6 as the feeler-member and its carrier 4 are driven

2

forward, and consequently the actuator misses the said engaging piece. This follows from the fact that when the feeler-tip is thus held from slipping the feeler-member 5 remains in contact with or close to the stop 11 on the feeler-carrier as the feeler-member and feeler-carrier are driven forward by the blow or pressure against the feeler-tip. When the supply of weft or filling within 10 the shuttle becomes so far depleted that it no longer is capable of preventing the feeler-tip from being deflected lengthwise of the weft-carrier by the forward blow applied through the weft-carrier, the resulting turning 15 movement of the feeler-member around its pivotal mounting 9 upon the feeler-carrier, the extent of which is limited by the stop 111 upon the said carrier, and which takes place before the feeler-carrier goes 20 forward, will throw the engaging end of the actuator into line with the engaging end-piece 6^a of the controller, so that in the forward stroke of the feeler-carrier the actuator will engage such end-piece and actuate 25 the controller. Thereby the controller will be turned around its pivot 7, from its normal position defined by a stop 17 upon the feeler-stand, against which the controller is held by the action of a spring 18. Substantially as in the Letters Patent aforesaid, as 30 the controller is thus turned, its extension 6^b will act against the cam-shaped portion 8^a of latch, catch, or dog 8 and turn the latter upon its pivot 8^b carried by the arm 19 35 mounted on the usual transversely-extending rockshaft below breast-beam 21. By this turning movement of the latch, catch, or dog its shoulder 8^c will be placed in the path of movement of a convenient striker 40 22, usually carried by the loom weft-hammer, and as a result of the engagement of the forwardly-moving striker with the latch, catch, or dog, the latter and arm 19 will be moved forward, and thereby the predetermined change in the operation of the loom 45 will be called through devices in operative connection with the arm 19 or the said breast-beam rockshaft. As the actuator disengages from the engaging piece 6^a of the controller, the spring 10 will turn the feeler-member 1 reversely upon its pivot 9 until it brings up against stop 11, the spring 18 will return the controller to its normal position against stop 17. As the return movement of 50 the controller causes extension 6^b to clear the cam-shaped portion 8^a of latch, catch, or dog 8, the overbalancing front arm of the latter will cause it to swing clear of the striker 22. As the lay recedes, the feeler-carrier 4 through the action of the contracting spiral spring 24, which is engaged with a short arm 4^b of the feeler-carrier, will be 55 swung rearward against a stop 23 upon the feeler-stand, which defines the normal or waiting position of the feeler-carrier.

The particular features in which the invention itself consists have not been mentioned thus far.

Letters Patent No. 1,127,086 show a feeler-tip having a single point or wedge-shaped 70 feeling end. Feeler-tips having broadened feeling-ends, in most cases toothed, serrated, or otherwise finished off for insuring better holding engagement with the exterior of the mass of weft or filling 75 b contained in a shuttle, have been employed extensively in practice. In the present instance, the feeler-tip 2 has its feeling or contacting end formed with blunt teeth. The character and shape of the toothing, roughing, or other engaging 80 or frictional facing may vary in the case of feeler-tips embodying the present invention. In conformity with the invention, the feeling or contacting end of a feeler-tip of the slipping class has a prominent blunt or 85 rounded nose 2^a and an inclined or sloping face 2^b, retreating forwardly from said nose to the other side of the feeler-tip. Consequently, if a bared or uncovered bobbin-barrel should be presented against the said 90 feeling or contacting end, the surface of said bare or uncovered barrel would make contact first with the nose 2^a. One object in giving this general form to the feeling or contacting end of the feeler-tip is to adapt 95 the feeler-devices for the use of wound weft or filling presenting to the feeler-tip an inclined portion of an interior which tapers toward the base or head of the weft-carrier, as in the case of the wound mass of weft or 100 filling shown in Fig. 1. Slipping feeler-tips of the kinds at present in use have a tendency to slip along the incline so as to cause a feeler-motion to call a change prematurely when such a reversely-tapered 105 mass as that shown in Fig. 1 is presented against one thereof. The retreating face 2^b of a feeler-tip embodying the present invention is adapted equally as well for use with a filling-mass having a reversely-tapered exterior as it is in the case of one so wound as 110 to present a parallel-sided portion of its length to the feeler-tip. This is due to the fact that the said retreating face substantially parallels the portion of the surface of 115 the filling-mass which is carried against the same by the advance of the lay, providing thereby for a comparatively extended flat contact of the feeler-tip face with the filling-mass, so that all the teeth thereof take hold, 120 without the liability of slipping heretofore experienced. As the weft or filling passes off from the weft-carrier so that a progressively denuding portion of the latter is presented to the feeler-tip, the rounded nose of 125 the feeler-tip receives the blow or pressure at successive beat-ups until it slips lengthwise of the weft-carrier. As this slipping takes place the feeler-member turns on its pivotal mounting so as to place the actuator 13

in line with the engaging portion 6^a of the controller. Such slipping also presents the inclined face of the feeler-tip in position to receive the pressure of the weft-carrier, 5 which thus acts against the entire length of such face in driving the feeler-member, feeler-carrier and controller forward so as to call the actuator into action upon the controller. In the slipping movement, the nose 10 is in advance of the face portion.

What is claimed as the invention is,—

1. Weft or filling-feeler device of slipping class, having a feeler-member provided with a slipping feeler-tip constructed with prominent nose and retreating face the latter extending obliquely substantially across the end of the tip, said nose leading in the slipping movement of the feeler-tip and feeler-member, and said retreating face adapted 15 for contact with the surface of a reversely-
- 20

tapered filling-mass to prevent premature slipping.

2. Weft or filling-feeler device of the slipping class, having a feeler-member provided with a slipping feeler-tip constructed with 25 a prominent smooth nose and a retreating roughened face, the latter extending obliquely substantially across the end of the tip, said nose leading in the slipping movement of the feeler-tip and feeler-member, 30 and said retreating face adapted for contact with the surface of a reversely-tapered filling-mass to prevent premature slipping.

In testimony whereof we affix our signatures, in presence of two witnesses.

GEORGE E. WHITEHEAD.

JAMES F. MARSHALL.
